UNITED STATES PATENT OFFICE.

AGNES C. FLIEGEL, OF NEW YORK, N. Y.

MILLINERY.

Application filed March 2, 1923. Serial No. 622,429.

To all whom it may concern:

Be it known that I, AGNES C. FLIEGEL, a citizen of the United States, residing in the city, county, and State of New York, have invented certain new and useful Improvements in Millinery, of which the following is a specification, reference being had to the accompanying drawings, illustrative of one particular embodiment of my invention.

10 My invention relates to millinery such as is used by women for covering or partially covering the head, but which may be readily removed, or may be readily converted for other use.

15 More particularly it relates to a head-gear which may be readily connected to form a turban or the like, for women's wear, and when so temporarily connected constitutes a visibly complete turban, toque or similar appearing article of millinery, but which may, at any moment, be partially separated so as to extend the material and fabric the full length of the periphery of the head, in order to constitute a shoulder 20 throw, boa or shoulder cape.

25 As a head-gear or shoulder cape it may be made of the usual fabric with ornamentation of flowers, artificial or real, or with ribbon, fur or other usual accoutrements, but may also be of basic material of a hat 30 permanently connected at one part of the periphery, and slit over the crown from such a point to a substantially diametrical- 35 ly opposite point where the peripheral or rim portions are severed, with readily connectable or separable means so as to form a complete head-gear unit, or when detached to form an extended member or apparel device which will readily fit over the 40 shoulders and the back of the neck, or may be otherwise disposed for convenience.

45 In some forms the construction lends itself to the formation of a hat in perfect assembly condition for head-gear, but quickly removable and convertible into a device or form of apparel convenient for disposal on lap, or otherwise, without injury to the material or ornamentation of the apparel, of great utility for theatre use and the like.

50 While numerous forms and decorations and designs may be applied or inter-woven into the carrying out of this invention, one particular embodiment is shown in the accompanying drawings forming a part hereof, in which:

Fig. 1 shows the article forming a normal head-gear or hat.

Fig. 2 is a perspective showing the same article as illustrated in Fig. 1, extended and forming a normal shoulder throw or collar- 60 ette.

Fig. 3 is a transverse section of the article when the parts are connected to form a hat.

Fig. 4 is a plan view of the inside of the 65 article when extended to form a neck throw, collar-ette or cape.

Fig. 5 is a fragmentary view of the junction of the two extended parts, with the extremities equipped in slightly modified 70 form.

Fig. 6 is a horizontal section of the extremities of the article at their juncture illustrating their union and adjustable connection for transformation into a hat. 75

The particular form thus illustrated, it will be seen by Fig. 1 constitutes a complete hat for women's wear comparable in every respect to a usual head-dress quite universally used. Fig. 2 illustrates the apparel 80 shown in Fig. 1 when opened up, that is, in part detached so that the entire periphery of the hat effect is extended so as to form an article of apparel fitting over the same woman's shoulders. In the latter form, the 85 particular design, construction or configuration enable the user to throw it about the shoulders, and depending upon the design and relative size of head and shoulders it may constitute a shoulder throw or what 90 is known as a cape or a collar-ette or a boa. The millinery art will serve to produce this combination, or as it may be called transformation, in innumerable ways as far as 95 size, design and artistic effect are concerned, and of any material desired which is usual for capes or neckwear and for hats, and likewise may be made of material or combinations varying with the seasons.

In Fig. 3, the construction is shown in 100 which the two parts 1 and 2 constitute side crowns when the article forms a hat, with a permanent union of these two sides at the seam 3, and with the interlining 4-4 and the band or head-size portion 5-5 and with 105 ornamentation 6-6, and top crown 7-7 of limp or suitable fluffy or other material slit from back to front.

As shown in this and other figures, the union of the slit 8 at the top is accomplished 110

by such readily detachable devices as snap fasteners 9—9^a, and the extremities, when the article is extended have readily detachable devices such as snap fasteners 10—10^a.

5 Close to one end I prefer to secure a linkage device such as 11, with retractable cord or chain 12 adapted to readily snap or hook into the device 13, when the article is thrown about the shoulders or neck.

10 As shown in Fig. 5, at least one of the detachable extremity snap sockets is multiplied so as to form a plurality 14, 14^a, 14^b providing means for a connection to vary the circumferential extent of the head size 5, in 15 order to more conveniently adapt a particular hat to the size of the user without any permanent or material change in the sewing or in the adjustment of the hair. The head size in women's close-fitting hats has a band 20 which is associated with the lower edge with material for hat band, lining or headsize of suitable degree of stiffness and suitable make-up and this lower portion of the up-standing parts with the band we call the 25 band portion. When this band portion has adjacent outside adornment or special finish, it constitutes what is called in this art a coronet. Such coronation is illustrated in the drawings and is clear from Fig. 1 as a 30 coronet in a hat, and in Fig. 2 constitutes the ornamental border of the article when converted into a shoulder throw, and the drawings in Fig. 3 illustrate at 6 elements of one form of ornamentation, which duplicated 35 around the border forms what is generally referred to in the trade as the "coronet."

It will thus be seen that the article, one form of which is specifically herewith shown and described is in its preferred form a unit 40 article, that is comprising essentially one piece, in the nature of a transformation from one use to another, namely, at the will of the wearer either for a hat, or momentarily, as desired, for a neck and shoulder 45 piece. This invention is of most marked utility for theatre or similar use. In such cases the removal of the hat is compulsory or desired, and invariably there is no suitable place to put a hat when removed, in a 50 theatre or the like, and in any event wherever disposed it is subject to damage or inconvenience. This invention not alone provides a convenient place to dispose the article when removed from the head, but it 55 serves the double purpose of providing the advantages of a neck or shoulder throw for protection against drafts and the usual matters of comfort, as well as appearance, which otherwise are served by the additional 60 article frequently worn for that purpose, thus making it entirely unnecessary to carry or wear a separate or additional article of apparel as is customary.

This transformation article therefore 65 serves for convenience and also for economy

in addition to the novelty and the protection against damage frequently involved in removing and handling a hat in the theatre, or on other occasions.

It also provides an article which may be 70 packed with greater convenience, and in the matter of private, as well as trade transport of these articles there is great advantage as compared with the complete and fixedly formed head-gear with its corresponding 75 ornamentation.

While in the particular form shown the permanent union of the head-band is shown at the front, in its form as a hat, and the detachable ends of the hat-band are shown 80 in the rear, various modifications may be made to suit the artistic or utilitarian aspect of these features. Various degrees of stiffness of hat-band and various make-up of material for hat-band, lining or head size 85 are all capable of variation to suit the taste or idiosyncrasies of the millinery art.

Various devices for connecting the detachable portions and connecting the intermediate material between the front and the 90 rear may be used, and, if desired, in some forms no fixed inter-connection of the crown or top portion need be used.

In any event the extended article of apparel with a certain amount of shape and 95 form advantageous in both forms of its use, provide for more or less fit or cling to the shoulders, and alternately a suitable shape for the hat effect.

While various changes may be made 100 without departing from the spirit of my invention, what I claim and desire to secure by Letters Patent is:

1. A head apparel for women comprising a turban with band portion and contiguous 105 upstanding side crowns, a contiguous top crown having a separable slit throughout, a slit severing the band portion registering with the slit in the crown, means for readily attaching or detaching the adjacent edges of 110 the crown and the ends of the band portion.

2. A transformable article of apparel, constituting in one form a shaped hat having a head size lower edge, adjacent up-standing formed side crowns and contiguous 115 crown with detachable parting across the entire crown, and in its alternate form providing a shoulder throw wherein the crown sides form a fitting shoulder covering and the band portion constitutes the border.

3. A collarette having a band edge, means for detachably securing the extremities thereof, two shoulder-fitting sides each projecting separately from respective halves of the band portion and completely disconnected from each other at their edges remote from the band portion, and means for connecting said sides whereby when the band portion ends are united the article is converted into a formed hat with head size and 125 130

upstanding side crown and interengaging top crown.

4. An article of women's apparel comprising in one form a shaped hat of adjustable head size, comprising band portion and adjacent foundation to form upstanding side crowns, a contiguous top crown, said crown portions having a slit throughout and a continuation of said slit extending through the band portion at one point, means for adjustably connecting the band portion to vary the head size, and means for interconnecting the sides of the slit of the remainder of the slit through the top crown, whereby separation of said slit provides an article in a form usable as a collarette to fit the shoulders and back of the neck.

5. A toque for women's wear consisting of a formed hat with band portion and crown, a separable transverse parting from one edge of the band portion therethrough throughout the crown, substantially invisible fastening for said parting edges when the article is used as a hat, whereby a toque

for regular wear which in appearance is a 25 completely formed hat, may be readily converted into a shoulder throw.

6. A woman's hat comprising a coronet associated with a headsize band separable at one place in the circumference, a two-part crown having a shaped upstanding portion in each part and having each part integral with and extending from one half of the headsize band, a soft top-crown portion integral with each shaped upstanding portion, and means for detachably securing the ends of the headsize band where separable and for entirely separating and connecting the adjacent edges of the top-crown portions.

In testimony whereof, I have signed my name to this application, in the presence of two subscribing witnesses, this 21st day of February, 1923.

AGNES C. FLIEGEL.
